UNITED STATES PATENT OFFICE.

WILLIAM HOMER TAYLOR, OF MEMPHIS, TENNESSEE.

DESIGN FOR A FENCE PANEL OR SIMILAR ARTICLE.

Application filed September 19, 1927. Serial No. 23,459. Term of patent 14 years.

To all whom it may concern:

Be it known that I, WILLIAM HOMER TAYLOR, a citizen of the United States, residing at Memphis, in the county of Shelby and State of Tennessee, have invented a new, original, and ornamental Design for a Fence Panel or Similar Article, of which the following is a specification, reference being had to the accompanying drawing forming a part thereof.

The figure is a perspective view of a panel or fence in accordance with my new design. The lining on the drawing indicates contrasting colors in which the various portions of the panels are painted.

I claim:

The ornamental design for a fence panel or similar article as shown and described.

In testimony whereof I hereunto affix my signature.

WILLIAM HOMER TAYLOR.
